Filed Nov. 19, 1973, Ser. No. 416,989

Term of patent 14 years

Int. Cl. D28—02

U.S. Cl. D86—10 G

FIG. 1 is a perspective view of the lipstick container with sliding mirror showing my new design in open position, the two hidden sides of the container in FIG. 1 being identical to the vertically disposed side seen in the figure;

FIG. 2 is a perspective view of the closed container;

FIG. 3 is a side elevational view thereof;

FIG. 4 is a top plan view; and

FIG. 5 is a bottom plan view.

I claim:

The ornamental design for a lipstick container with sliding mirror, substantially as shown and described.
